UNITED STATES PATENT OFFICE.

WILLIAM E. BUDD, OF CHATHAM, NEW JERSEY.

BREECH-LOADING FIRE-ARM.

SPECIFICATION forming part of Letters Patent No. 291,980, dated January 15, 1884.

Application filed June 2, 1883. (No model.)

To all whom it may concern:

Be it known that I, WILLIAM E. BUDD, of Chatham, in the county of Morris and State of New Jersey, have invented certain new and 5 useful Improvements in Breech-Loading Fire-Arms; and I do hereby declare the following to be a full, clear, and exact description of the invention, such as will enable others skilled in the art to which it pertains to make and use 10 it, reference being had to the accompanying drawings, which form part of this specification.

My invention relates to an improvement in breech-loading fire-arms; and it consists, first, 15 in the combination of the pivoted operating-lever, which extends backward over the grip of the stock, a spring-snap for locking the lever in place, and an arm, which is pivoted both to the lever and to the barrels, for the 20 purpose of moving the barrels lengthwise upon the stock; second, in the combination of the endwise-sliding barrels, which are provided 25 with a series of projections upon the top of their rear ends, with a perforated arm, which 30 closes down upon the projections, and an operating-lever, by means of which the barrels are moved back and forth; third, the combination 35 of the operating-lever, the connecting rod or arm, which is placed between this lever and the endwise-sliding barrels, the connecting 40 arm or rod being grooved upon its top, so as to guide the eye in taking sight; fourth, the combination of the operating-lever, the arm connected thereto, and the vertically-moving spring-actuated cartridge-extractors, which 45 are operated by the movement of the connecting rod or arm as it is raised and lowered in respect to the barrels and the main frame; fifth, the combination of the operating-lever, a rod or arm connected thereto and to the endwise-sliding barrels, the main 50 frame, cocking-plates provided with lugs, and the hammers; sixth, in vertically-moving spring-actuated cartridge-extractors, which 55 are adapted to be moved by the hand, and which act as cartridge-extractors, indicators, and safety attachments to prevent premature explosions; seventh, the combination of the hammers, the sliding blocks or tumblers, the 60 vertically-moving spring-actuated cartridge-extractors, and the triggers; eighth, the com-

bination of a single trigger-plate, the two triggers arranged together, and a single spring for operating both triggers and the sears connected to them; ninth, a mainspring which 55 is bent at right angles, and which has its two ends to diverge, so as to operate in two directions at once for the purpose of operating the hammer, holding itself in position, and to give additional force.

Figure 1 is a side elevation of a gun embodying my invention complete, showing the gun closed. Fig. 2 is a similar view, showing the gun open and the thumb-piece used in connection with the hammer and the sliding 65 side plates removed so as to show the lock. Fig. 3 is a vertical longitudinal section taken to one side of the center, so as to show the operating parts and the manner of attaching the connecting rod or arm to the barrels. Fig. 70 4 is a plan view. Figs. 5, 6, 7, 8, 9, 10, 11, 12, 13, 14, and 15 are detail views.

A represents the stock, B the main frame, and C the barrels. Upon the top of the forearm of the stock rests the extension D of the 75 main frame B, which is provided with a dovetail groove. The barrels C have a corresponding dovetail plate or piece attached to the under side, so as to catch in this groove, and thus hold the barrels in position upon the forearm while moving endwise back and forth. In the top of the barrels, at a suitable distance from their rear ends, is made a suitable depression, which is cut under at its rear end, and in which the pivoted fastening-piece E, 85 which is connected to the connecting rod or arm F, is made to catch. This fastening-piece has its inner end made pointed, and catches under this cut in the end of the recess, so as to fasten the barrels and the connecting rod 90 or arm together. The top rib of the barrel has a small piece, G, cut away and then pivoted in position, and the rear end of this pivoted piece G of the rib is made to catch over the front end of this fastening device E, and 95 thus lock it securely down in the recess in which it is made to catch. As this pivoted locking-piece E is held at its front end by means of the pivoted part G of the rib, and at its rear end by means of the cut in the 100 end of the recess, it will readily be seen that this part is held rigidly in place when

locked; but it is adapted to be quickly disengaged by simply turning the part G at right angles.

The pivoted arm or projection F is fastened 5 to the endwise-sliding barrels at its front end by means of the locking device, and to the operating-lever H at its rear end. This operating rod or lever is made grooved upon its top, so as to guide the eye in taking sight, and thus 10 prevent the person using the gun from sighting from any other part than directly along the rib. Where there is nothing to guide the eye, a person who is taking a quick aim is liable to sight diagonally across the barrels, and hence 15 miss their mark. By making this arm F grooved, as is here shown, the sportsman always has an absolutely sure guide in taking aim. In order to lock the barrels and this connecting arm or rod together when the barrels 20 are closed, and thus lock them rigidly in place, there are a number of projections, I, formed upon the top of the rib of the barrels, as shown, and in the connecting arm or rod are a corresponding number of perforations, in which 25 these projections are made to catch when the rod or arm is forced down upon the top of the barrels. These projections will preferably be made to pass directly down through the web of the barrels, and through the plate, which 30 is secured to their under sides, and their upper ends will preferably be set at nearly right angles to the barrels of the gun, so as to cause them to hold the barrels more rigidly in position when they are closed. This connecting 35 rod or arm is attached at its rear end to the operating-lever, and when the operating-lever is raised the connecting rod or arm forces the barrels outward, and at the same time raises the connecting-rod upward, so as to allow ample 40 room for the insertion and removal of the cartridges. When the lever is depressed, as shown, this connecting rod or lever is depressed upon the barrels and the main frame, and made to operate the vertically-moving 45 spring-actuated cartridge-extractors, as will be more fully described hereinafter. This connecting rod or arm differs from those which have heretofore been used for moving the barrels endwise, in that it is placed directly upon 50 the top of the barrels, where it is always in sight, and where it can be readily inspected and examined. One great advantage in placing this rod or arm upon the top consists in cheapening and simplifying the construction 55 of the gun, and making it much easier to construct the arm or rod than it would be if the arm or rod were concealed and had to work through other parts. Through the rear end of this connecting rod or arm is made an opening, J, which, when the operating lever and rod are closed down, catches over a rearwardly-projecting horn or projection, J', which, catching in this opening J, helps to brace and hold the different parts rigidly together.

60 65 The operating-lever H is pivoted at its front end in a slot in the top of the main frame B,

and extends rearwardly along over the top of the grip of the stock. Through this main frame and in the grip of the stock is made a suitable groove, in which the lever sinks, so 70 that when the lever is closed it does not extend above the grip, so as to be in the way of the hand in taking hold of the stock to use the gun. Upon the rear end of the lever is formed a small ring or handle, M, which is adapted to engage 75 with a spring snap or catch, N. As the lever is forced downward the snap locks it in position, and the lever can only be raised upward by first disengaging the snap or catch, which is readily done with one of the fingers as the gun 80 is taken hold of. Should the lever at any time be only partially raised, the very act of grasping the gun by the grip will cause the lever to sink down into this position, and thus place it in 85 position for firing. When it is desired to bring the safety-catch into use, it is only necessary to disengage the rear end of the lever from the snap or catch, when the rear end will rise up a slight distance, and in rising upward it allows 90 the connecting rod or arm to rise a slight distance upward with it, and as the rod or arm rises upward the vertically-moving spring-actuated cartridge-extractors are allowed to rise upward, and thus act as safety-catches to prevent 95 premature explosions. Connected to this lever near its front end is the connecting-rod O, which has attached at its lower end suitable 100 projections, which pass through the cocking-plates P. These projections, which unite the cocking-plates and the rod or arm, move back and forth through curved grooves, which are 105 made in the main frame. These cocking-plates are both pivoted at their lower front ends, preferably upon the same bolt or rod. Upon the upper front end of each plate is formed a lug, Q, 110 which engages with the hammers for the purpose of full-cocking them. The inner sides of the hammers are shaped preferably as shown in Fig. 5, so that when the lug upon the cocking-plate first engages with the hammer it exerts a direct backward pull upon it, and as the 115 pull is continued the lug slides off from the hammer and leaves it at full-cock. The hammer and the cocking-plate being pivoted at different points, the lug upon the cocking-plate is constantly rising upward and backward over the edge of the hammer as the cocking-plate 120 is being drawn backward by the action of the operating rod or arm.

The hammers R consist of a single straight 125 piece of metal, and are pivoted at their lower ends upon removable plates S, which are held in place in the slots O' in the main frame by means of screws T. The upper rear corners of these hammers are provided with set-screws 130 U, by means of which thumb-pieces can be applied to the hammers when it is desired to use the hammers in the ordinary manner. Some persons desire to use what is called a "hammerless" gun, while others always prefer to have the hammers to operate in the usual manner. In order to adapt the gun to be used

as a so-called "hammerless" gun, or as a gun having hammers in sight, this hammer is adapted, by means of the set-screw U, to have the thumb-pieces attached or not, as may be preferred. The hammer and all of its attachments are placed in a recess made in each side of the main frame B, and this main frame is provided with grooves in which the edges of the covering-plates V are made to catch. 5 When the hammer is used without the thumb-pieces, these plates will be inserted in the groove, and they will then conceal the hammer and all of the parts connected therewith. 10 When, however, the thumb-pieces are to be used in connection with the hammer, these plates are to be removed, and then the hammer and nearly all of its attachments will be in full view. By means of this construction the same gun may be adapted for two different persons 15 having different tastes in regard to hammers, and will enable a salesman to convert the gun into either kind of weapon, as the tastes of the purchaser may dictate, without having to keep a double assortment of guns upon hand. These 20 removable plates allow the whole lock of the gun to be inspected at any moment, either for the purpose of cleaning them, oiling them, or for any other purpose. Where the plates are not used and the parts are left exposed, the 25 parts are so few and simple that no ordinary amount of exposure or hard usage is liable to injure them in the slightest.

The mainspring W consists of a flat piece of metal, which is first doubled upon itself and 30 then bent at right angles, and has its two ends to approach each other, as shown. These springs have one end to engage with the rear side of the hammer, while the other end engages with the plate to which the hammer is 35 pivoted. The vertical portion of the spring bears against the forwardly-inclined portion of the recess in which the hammer is placed, and has its ends to operate in different directions. By thus having its two ends to bear in 40 opposite directions the spring exerts its pressure both in operating the hammer and in holding itself in position, and at the same time follows the arc of the hammer without the necessity of any intermediate connecting-link, in the 45 usual manner, thereby simplifying and cheapening the construction of the lock.

Connected to each hammer at any suitable distance above its pivotal point is the connecting-rod X, which rod X has its front end 50 attached to the sliding block or tumbler Y. This block or tumbler Y slides back and forth through an opening which is made in the main frame, and passes through the recess which is made in the lower end of the cartridge-extractor Z. In the lower edge of each 55 block or tumbler are made the two notches 1, which represent full and half-cock, in the usual manner, and upon the opposite edge is formed the safety-notch 2. When the hammer is 60 drawn backward, this block or tumbler is drawn back a corresponding distance by means

of the connecting-rod, so as to leave the hammer at full-cock.

Upon the trigger-plate 3 are pivoted, side by side, the two sears 4 and the two triggers 5. A single spring, 6, is secured upon the top of this trigger-plate, and this spring is divided into two prongs, as shown. Each prong bears upon the top of the rear end of each sear. The pressure of this spring upon the rear end of 70 the triggers always returns them to position, and the upward pressure against the rear end of the sears keeps them always forced upward, so as to engage with the notches of the sliding block or tumbler. Upon the rear end of each 75 sear is formed an extension or shoulder, 7, and upon the front upper corner of each trigger is formed a projection, 8, which catches over this rear end of the sear, and thus causes the two parts to always move together. When 80 the trigger is pulled, this extension formed upon its front upper corner pulls down upon the rear end of the sear, and as soon as the trigger is released the pressure of the spring forces both the trigger and the sear to return 85 to position. When one of the triggers is pulled, the sear is forced downward, so as to become disengaged from the sliding block or tumbler. Also, secured upon the trigger-plate is a double-pronged spring, 9, which has its prongs 90 catch against small shoulders formed upon the lower ends of the vertically-moving cartridge-extractors Z and keep them forced upward 95 when the connecting rod or arm which moves the barrels leaves them free to move. These 100 cartridge-extractors Z are provided with a flange, 10, at their upper ends, for the purpose of catching over the flange of the cartridge; but this flange does not connect with the cartridge until the lever has been depressed, so as to close the connecting rod or 105 arm down upon them. When the connecting rod or arm is raised upward, the pressure is removed from the upper ends of these cartridge-extractors, and they at once are forced 110 upward by means of the spring 9, so that the gun may be opened without affecting the cartridge in any manner. The connecting rod or arm is made to hold these cartridge-extractors 115 down in place by bearing upon the shoulders 11, which are formed upon their inner sides. After one of the barrels has been fired, the sliding block or tumbler Y, connected with the hammer of the barrel which has been fired, is forced forward through the recess in the side 120 of the extractor until the shoulder A' upon the block rests inside of the recess in the side of the extractor, and thus prevents the extractor from rising. As long as the extractor is thus locked down in position the flange 10 upon 125 the front upper face of the extractor is locked down upon the edge of the cartridge, and when the gun is opened the extractor holds the cartridge stationary, while the barrels are pushed forward away from it, and then the 130 cartridge is ejected by the spring B', which is secured to the breech-plug C'. Also, formed

in the inner side of each one of the sliding blocks or tumblers, just in advance of the shoulder A', is the recess 2, which serves as a safety-notch to prevent a premature explosion. When the lever is partially raised and the hammer at full or half cock, the sliding tumbler or block is drawn backward, so that the recess 2 comes just over the lower end of the recess formed in the side of the extractor, and as the extractor is forced upward by the spring 9 the lower end of this recess in the extractor catches in the recess 2, formed in the block, and thus prevents the hammer, in case the trigger is pulled, from flying forward far enough to strike the firing-pin. The sliding block or tumbler will slide back and forth over the cartridge-extractor the full length of the recess 2, and this recess 2 will serve as a safety-notch under all circumstances, because if the trigger is pulled the hammer can only move forward the length of the slot 2, and no farther. When, however, the operating-lever is fully depressed, the connecting rod or arm bears upon the top of the cartridge-extractor and forces it down below the level of the shoulder A' upon the block, and then the block can slide forward the full length necessary to let the hammer strike the firing-pin when the trigger is pulled. The firing-pins are placed in the screw-cylinders E', which extend through the main frame and through the opening F' in the upper end of the cartridge-extractor, and screw into the breech-blocks, to which ejector-springs are secured. Projecting out from each of the breech-blocks, at their lower inner edge, is a supporting-pin, G', which prevents the cartridge from dropping downward.

In case it should be desirable or necessary to use an additional device for locking the barrels in place, the pivoted locking-lever B" will be used. This is pivoted at its front end to the extension D, and has formed upon its rear end a notch or shoulder to engage with a corresponding notch or shoulder formed on the under side of the barrels. The rear end of this locking device extends backward far enough to have its rear end operated upon by means of the operating-lever, so that whenever the operating-lever is raised this locking device will have its rear end depressed sufficiently to loosen the barrels, when they will be left free to move. This locking device may or may not be used in connection with the gun, as may be desired.

When it is desired to place the gun at half-cock when concealed hammers are used, the operating-lever H must be depressed into position, so as to draw the hammer back to full-cock, and then the rear end of the lever H is detached from the spring-snap N and raised slightly upward. This slight upward movement of the rear end of the lever allows the cartridge-extractors to rise upward into the safety-notches 2 of the sliding blocks Y, and

then when the triggers are pulled the hammers will move forward to half-cock.

The great object gained by placing the connecting rod or arm F upon the top of the rear end of the barrels consists in having it rest directly upon the top of the barrels, so as to relieve the strain on the main frame at the base of the barrels and make the gun stronger, while it enables a lighter main frame to be used. The rear ends of the barrels are then held between the extension D and this arm or lever, which is locked rigidly in place. Bracing the barrels both above and below, as is here shown, makes it unnecessary to use as heavy or strong material in making the gun, and hence the gun is both light and durable.

The cartridge-extractors serve as indicators, to show whether either one of the barrels has been fired by its raised or depressed position when the operating-lever is partially raised at its rear end. If either one of the cartridge-extractors remains depressed, a person sees at a glance that the falling of the hammer has pushed the sliding block or tumbler Y forward, so that the shoulder A' catches in the recess made in the side of the extractor, and thus prevents the extractor from rising upward.

Having thus described my invention, I claim—

1. In a breech loading fire-arm, the combination of the operating-lever, which is pivoted in the top of the main frame and extends backward over the grip of the stock, the endwise-moving barrels, and the connecting rod or arm which connects the lever and the barrels together, and which rod or arm is placed above the rear end of the barrels, substantially as shown.

2. In a breech-loading fire-arm, the combination of the operating-lever, which is pivoted in the top of the main frame, and which extends back over the grip of the stock, the endwise-moving barrels, the connecting rod or arm, which is placed above the rear end of the barrels, and which serves to connect the operating-lever and barrels together, the pivoted fastening device, and a means for fastening the device to the barrels, substantially as described.

3. In a breech-loading fire-arm, the combination of the operating-lever pivoted upon the top of the main frame and extending back over the grip of the stock, the endwise-moving barrels, the connecting rod or arm which connects the lever and barrels together, and which is placed above the rear end of the barrels, a means of connection for the connecting-rod with the barrels, and a guide or way placed upon the forearm for the barrels to slide upon, substantially as set forth.

4. In a breech-loading fire-arm, the combination of the operating-lever, pivoted in the main frame and extending back over the grip of the stock, the spring-snap N, for locking

95

105

110

115

120

125

130

the lever down in place, the endwise-moving barrels, the connecting-rod placed above the rear end of the barrels and connecting the barrels together, a means of connection between the rod and the barrels, and a guide or way placed upon the forearm for the barrels to slide upon, substantially as specified.

5. In a breech-loading fire-arm, the combination of the operating-lever, the endwise-moving barrels, and the rib F, which is loosely connected to both the lever and barrels, the rib being grooved upon its top, so as to aid in directing the aim, substantially as shown.

6. In a breech-loading fire-arm, the combination of the endwise-moving barrels provided with the projections I, with the perforated connecting rod or arm placed above the rear end of the barrels, and adapted to close down upon them, and the operating-lever H, substantially as described.

7. In a breech-loading fire-arm, the combination of the lever H, pivoted upon the top of the main frame, the rod O, provided with the projections for engaging with the cocking-plates, and pivoted to the lower edge of the lever H, the slotted main frame, the cocking-plates, and the hammers, substantially as set forth.

8. In a breech-loading fire-arm, the combination of the main frame, having a recess formed in its side or sides to receive the hammer and spring, with a mainspring, which is formed from a single piece of metal, which is bent double and then bent at right angles, the side of the recess against which the bent portion of the spring rests being inclined forward, so as to hold the spring in place, substantially as specified.

9. In a fire-arm, the combination of a hammer, the plate S, to which the hammer is pivoted, the main frame provided with slots through which the plates are passed, set-screws

for holding the plates in place, and a spring, which has one end to catch against the plate and the other against the hammer, substantially as specified.

10. In a fire-arm, the combination of the operating-lever H, connecting rod or arm F, and the vertically-moving spring-actuated cartridge-extractors, which are depressed upon the cartridge by the rod or arm when the gun is closed, substantially as shown.

11. In a fire-arm, the combination of a hammer, a connecting-rod attached thereto, a sliding block attached to the front end of the connecting-rod and provided with a safety-notch, and notches in which the sear catches, and the vertically-moving spring-actuated cartridge-extractor, which engages with the safety-notch to prevent premature explosions, substantially as shown.

12. In a fire-arm, the combination of the trigger provided with a projection on its front end, the sear having an extension on its rear end, the spring 6, which engages with both the sear and trigger, and the notched sliding block, which is moved by the hammer, and with which the sear engages, substantially as described.

13. In a fire-arm, a vertically-moving cartridge-extractor, in combination with the spring 9, which presses the extractor upward when the extractor is left free to move, the sliding block, and trigger, whereby the extractor serves as an indicator to show whether the barrel has been fired, substantially as set forth.

In testimony whereof I affix my signature in presence of two witnesses.

WM. E. BUDD.
